UNITED STATES PATENT OFFICE.

JAMES H. BLESSING, OF ALBANY, NEW YORK, ASSIGNOR TO THE ALBANY STEAM TRAP COMPANY, OF SAME PLACE.

COMBINED AIR AND CHECK VALVE.

SPECIFICATION forming part of Letters Patent No. 241,597, dated May 17, 1881.

Application filed December 22, 1879.

To all whom it may concern:

Be it known that I, JAMES H. BLESSING, of the city of Albany and State of New York, have invented a new and useful Improvement in Combined Air and Check Valves, of which the following is a full, true, and exact description, reference being had to the accompanying drawings.

In the use of steam-coils for heating considerable quantities of air are released in the pipes, which it is most desirable to expel from them in order to secure the proper operation of the heating apparatus. It is therefore very important to place at the end of the return or elsewhere air-valves which may pass out such air from said pipes, leaving the steam within. It is also very important that when the pressure within the pipes becomes reduced below that of the atmosphere the air without shall find no opportunity of returning. A check-valve is ordinarily employed to prevent this return, but with this disadvantage: that the steam or air escaping past such check-valve when raised is very liable to cut its face and prevent the proper seating of the valve.

The form of valve shown in my drawings is designed to pass out air gradually whenever the pressure is above that of the atmosphere, but to seat closely whenever the pressure in the coils becomes lower than that of the atmosphere. To accomplish this my valve is provided with two independent operative portions, which are, however, connected together, one of which is arranged to almost seat when the valve is in a certain position, the other of which is arranged to seat the valve closely whenever the pressure within is below that of the atmosphere.

Figures 1 and 2 represent vertical sectional views of my valve in its lower and upper positions.

Similar letters refer to similar parts in both figures.

The valve is connected to the coil or other space containing air by pipe P. The escape to the atmosphere is by pipe R. The valve A is inclosed in valve-chamber B, and seats upon the central horizontal partition, C. The upper end of said valve is guided by means of an adjustable tube, D, the end or pin connected

with said valve sliding freely within said tube. The valve itself consists of two cylindrical sections suitably connected, the upper of which, E, seats closely on the upper side of the partition C. The lower one, F, is so arranged that it can enter the tubular opening in the partition C.

When in operation the valve should be adjusted as in Fig. 2, so that when in its upper position, as there shown, an annular opening 60 is left between the valve F and the partition. The advantages of this arrangement will be readily understood. When the steam-pressure is on the valve, which is its ordinary condition of operation, it is in the position shown 65 in Fig. 2 when the air escapes past it, as indicated by the arrows, all the wearing and cutting action of said air being expended upon the corners of the partition and the upper corners of the lower valve, F. The valve E being 70 elevated out of the way of the outflowing currents is therefore not affected or cut by them. When, however, the valve seats as in Fig. 1 the upper or check portion of the valve E seats closely on the upper side of the partition, and 75 both partition and valve being unworn said seat is tight.

Of course this valve can be used with an independent expansion-valve, if desired, or it may be used in the manner shown, which allows of a little leak or escape whenever the pressure within the pipes is above that of the atmosphere, but closes tightly when such pressure becomes reduced below that of the atmosphere.

By means of the adjustment D the leak can be varied to any desired extent, and any wear or cutting upon the valve F can be readily compensated for by allowing the valve to enter farther in the annular opening of partition C.

What I claim as my invention, and desire to secure by Letters Patent, is—

1. A compound air-valve composed of two independent disks permanently connected together, one of which operates as a tightly-closing check-valve and the other as an air-escape valve, substantially as described.

2. A compound air-valve composed of two valve-disks and a connecting stem, one of which

acts as a tightly-closing check-valve against a permanent seat and the other as an air-escape valve, the position of said escape-valve with reference to its seat being adjustable by means of a screw, substantially as described.

3. A compound air-valve which consists of two disks, E and F, connected by a stem, the valve E serving as a permanent and tight check,

the valve F as an air-escape, said valve F being adjustable with reference to its seat by means of a screw, D, substantially as described.

JAMES H. BLESSING.
